SPRING BAR

Robert H. Konikoff, Jackson Heights, N. Y., assignor to Hammel, Riglander & Co. Inc., New York, N. Y., a corporation of New York

Application April 21, 1944, Serial No. 532,187

1 Claim. (Cl. 24—265)

This invention relates to spring bars of the character intended for use on wrist-watches to form anchorages for the wrist strap. As is well understood, these spring bars extend between the lugs on the wrist-watch case, and are provided with spring-pressed studs or trunnions at their ends for entry into the aperture or holes in the watch case lugs. Due to the limited movement of these studs or trunnions, the spring bars of conventional construction must be made in a relatively large number of sizes to enable them to fit the various sizes of watch cases.

An object therefore, of the present invention, is to provide a spring bar having a relatively large capacity for expansion and contraction to enable it to fit a large number of wrist-watch sizes, thereby requiring the merchant or jeweler to carry only a minimum number of differently-sized spring bars in stock.

Another object of the invention is to provide a spring bar of this character in which the number of parts required is decreased, in which means are provided by which the trunnions will fit both open and so-called "blind" holes in the watch case lugs; in which the assembly of the spring bars during manufacture is greatly facilitated, and which can be more readily applied to the watch and to the wrist strap by the merchant, manufacturer or jeweler.

In the accompanying drawing, wherein an illustrative embodiment of the invention is shown, Fig. 1 is a side view of the improved spring bar with the greater part of the same shown in section; Fig. 2 is an enlarged side elevation of one of the trunnions of the spring bar; Fig. 3 is a side view of the second trunnion or sleeve member, with a part broken away to disclose the hollow or tubular part of this element; Fig. 4 is a view looking to the left end of the trunnion shown in Fig. 2, and Fig. 5 is a sectional view on the line 5—5 of Fig. 3, looking in the direction of the arrows.

The spring bar consists of only three main elements, namely, the sleeve-like outer member or trunnion 1; the rod-like inner member or second trunnion 2, and the coil spring 8 which extends between and tends to normally spread the two trunnions apart. The member 1 is solid at the right end, as viewed in Fig. 1 and this solid end 1a is formed with the stud 5 receivable in a watch-case lug aperture, the adjacent collar 4, and the neck portion 3, all of these elements being integrally formed as a part of the member 1. The member 1, being hollow for a considerable part of its length, is thus provided with the bore

5, extending for a portion of its length, said bore containing the coil spring 8 having one end bearing against the end wall 7, or inner end of the solid portion of the member 1, and having its other end operative against the inner end of a head 13 integrally formed on the inner trunnion 2.

The trunnion 2 is of solid, rod-like formation, as clearly seen in Fig. 2, and is provided at one end with the stud 9 receivable in the second hole in the watch-case lug. A collar 10 is formed adjacent to the stud 9, the purpose of which is to enable the finger-nail or an instrument, to engage the face 11 and retract the trunnion 2 when it is desired to disengage the stud 9 from the watch-case aperture to free the spring bar from the watch.

Between the collar 10 and the head 13, which is also of collar-like-formation, is a lengthy shank portion 12 of greater length than the collar 10 or the head 13, and of less diameter than either of these two elements, said shank portion sliding freely through the entrance opening 16 to the bore 6. The opening 16 is surrounded by the inturned annular flange 15 adapted to abut 25 against the end 14 of the head 13 when the two telescoping parts 1 and 2 are separated to their greatest extent by the pressure of the coil spring 8, as shown in Fig. 1.

The spring bar in its normal or inoperative position, is shown in Fig. 1, wherein the two telescoping parts 1 and 2 are separated to their greatest extent by the spring 8. Due to the fact that the solid, rod-like member 2 has the shank portion 12 of considerable length, it can be brought 30 within the sleeve portion 6 of the member 1 to any extent required to regulate the effective overall length of the spring bar to enable it to fit a great number of differently-sized watch-cases. The semi-solid nature of the outer member or sleeve 1 and the solid rod formation of the inner member 2 provides for strength and enables the spring bar to withstand strap pull. The assembly 35 of the spring bar is very simple, due to the fact that all of its parts are relatively large, as compared to those employed in conventional types, and a minimum of parts are employed. In the assembly of the device, the spring 8 is dropped in place in the bore 6; the member 2 is inserted, and then the flange 15 is inturned, the parts being held in their operative relations thereby.

To remove the spring bar from the watch, the finger nail or a small instrument is placed against the collar 10 and the trunnion 2 is retracted to an extent necessary to free its stud from the aperture in the watch-case lug.

Having described one embodiment of my invention, it is obvious that the same is not to be restricted thereto, but is broad enough to cover all structures coming within the scope of the annexed claim.

What I claim is:

A spring bar consisting of two trunnion members, one of which is a solid rod and the other of which is a sleeve provided with a solid end part formed with a stud for reception in the aperture in a watch-case lug, the rod being slidable within

the sleeve for the greater part of its length to regulate the overall length of the spring bar, the rod having a head within the sleeve, an inturned flange on an end of the sleeve for limiting movement of the rod in one direction, a spring in the sleeve operative against the head for urging the rod in said direction, said spring bearing against the solid end of the sleeve, a stud integrally formed on the rod, and a collar located adjacent to the stud.

ROBERT H. KONIKOFF.
